Primary Examiner — Alison M Ofstun*(74) Attorney, Agent, or Firm* — FASKEN MARTINEAU DUMOULIN LLP; Serge LaPointe(57) **CLAIM**

The ornamental design for a bus bar for wind turbine, as shown and described.

DESCRIPTION

FIG. 1 is a perspective view of a bus bar for wind turbine, showing our design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The bus bar for wind turbine is shown with a symbolic break in its length and height as illustrated with the dash-dot broken lines. The appearance of any portion of the bus bar for wind turbine between the break lines forms no part of the claimed design.
